UNITED STATES PATENT OFFICE.

NICK K. RAMOS, OF LANSING, MICHIGAN.

LIFE-PRESERVER.

1,178,874.

Specification of Letters Patent. Patented Apr. 11, 1916.

Application filed October 6, 1915. Serial No. 54,421.

To all whom it may concern:

Be it known that I, NICK K. RAMOS, a subject of the King of Greece, residing at Lansing, in the county of Ingham and State 5 of Michigan, have invented certain new and useful Improvements in Life-Preservers, of which the following is a specification.

My invention relates to a life preserver of that type which, while completely inclosing and protecting the body of a person, 10 permits movement of the limbs for the purpose of propulsion.

One object of this invention resides in providing a novel form of waterproof bag 15 of a flexible nature and having buoyant means so arranged as to support the bag in a proper position in the water.

Another object resides in the shape of the bag which, when opened for occupancy, is 20 similar to a closed deck boat.

A further object resides in the particular means for ingress and egress and which, when closed, forms a water tight joint. And a still further object resides in the 25 novel arrangement of observation windows, air tubes and means for attaching tackle to lift the device out of the water.

With the above and other objects in view 30 I will now proceed to describe a specific form of the invention, as illustrated in the accompanying drawing forming a part of this specification and in which:

Figure 1 is a side elevation of the life 35 preserver showing an occupant in dotted lines. Fig. 2 is a top plan view, and Fig. 3 is a transverse section on the line 3—3 of Fig. 2.

In detail: The invention, as shown in the drawing, comprises a substantially rectangular frame 1 of wood or other buoyant 40 material, to which the members 2, forming a pocket book closure, are hinged at 3. The frame 1 has secured thereto a waterproof bag 4 of suitable flexible waterproof fabric, 45 and further, this material is extended to cover the members 2. The members 2 carry packing elements 5 which abut when said members are in the closed position and thus form a water tight joint. Also one of the 50 members 2 has riveted thereto at 6 a sheath 7 which, when said members 2 are closed, overlaps the opposite member 2 to protect the joint therebetween. Also on the inner 55 edges of the members 2 handles 7' are provided which permit the person to close the device after occupying the same. The said

members 2 are maintained in a closed position by the lock 8 which is only operable from without by means of the key member 9, thus there is no danger of the occupant 60 opening the device before being picked up by a rescue party. Since if the device could be opened from within the occupant might accidentally open the same at such a time that it would immediately fill the device 65 with water and drown the occupant.

To admit air to the interior of the bag 70 flexible breathing conduits 10 are provided which have downwardly turned ends to exclude water and are fastened in position by 70 clips 11 screwed or otherwise secured to the members 2.

On opposite sides of the device and substantially co-extensive in length with the frame 1, are the buoyant members 12 and 75 located directly beneath the members 12 are buoyant fins 13 which are hinged at 14 so as to fold. Also at each extremity of the boat like bag 4 is a float 15. All of these 80 buoyant members are preferably of cork and are covered by the same waterproof fabric of which the bag 4 is constructed, any seams being suitably reinforced so as to be water-tight. Furthermore when the device is 85 folded it may be strapped together by straps 16.

At the head end of the boat like bag, and in what may be suitably termed the upper deck thereof are provided the observation 90 windows 17. Also in the sides of the bag, 90 at the head and foot ends thereof are flexible members or coverings 18 to receive the arms and 19 to receive the legs which thus 95 permits the occupant to use his limbs to propel the device without exposing the same to voracious marine creatures and to the deleterious action of the sea water.

It will be evident from the construction described in the foregoing paragraphs that, when not in use, the device may be compactly folded and stored away in substantially the same manner as the usual belt life preserver and also it does not require a great deal of space. Furthermore in use it completely incloses the person and is therefore 100 much more practical than a belt life preserver.

In use, after untying the straps 16 and opening out the life preserver as shown in Figs. 1 and 2, the user disposes himself 110 within the same in the position shown in Fig. 1, that is with his arms in 18 and legs

in 19 and with his head directly beneath the observation windows 17, and a suitable mattress 20 of buoyant material and doubled over at 21 to provide a head and back rest 5 is provided which while adding to the comfort of the occupant of the device also adds considerable to the stability and serviceability. When the occupant is in the position shown in Fig. 1, the closure members 2 10 are locked and the device lowered into the water by means of suitable tackle attached to eye bolts 22. It will be apparent that enough provisions to last for some days may also be stored within the device. And 15 therefore reasonable comfort is afforded the occupant. In rescuing the rescue party may withdraw the device from the water by suitable tackle hooked in eye bolts 22 and may open the closures 2 by means of key member 9.

While I have herein described and illustrated a specific embodiment of my invention, it is nevertheless to be understood that, in practice, various modifications may be resorted to without departing from the spirit of the invention as defined in the appended claims.

I claim:

1. A life preserver including a water tight compartment adapted to receive a person, buoyant means carried fore and aft and on the port and starboard sides of said compartment to support the person in a substantially lateral position when said life preserver is in the water, and means incasing and yet permitting propulsion movements of the limbs exteriorly of said compartment in a lateral plane.

2. A life preserver including a substantially rectangular frame, a boat like bag attached to said frame, closure members carried by said frame, air tubes, and buoyant means carried fore and aft of said bag and on the port and starboard sides of said frame.

3. A life preserver including a substantially rectangular frame, a boat like bag of flexible waterproof material carried by said

frame, a pocket book closure for said bag also carried by said frame, means for imparting buoyancy to said life preserver, and means to cover and yet permit movement of the limbs of a person exteriorly of said bag. 50

4. A life preserver including a substantially rectangular frame of buoyant material, a boat like bag of flexible waterproof material carried by said frame, a pocket book closure for said bag also carried by said frame and of buoyant construction, means disposed in a lateral plane for imparting buoyancy to the life preserver, and means permitting movement of the limbs of a person exteriorly of said bag. 55

5. A life preserver including a flexible bag having a water tight closure, said bag 60 being of boat-like configuration, floats flexibly connected with said bag on the port and starboard sides thereof, and other floats carried fore and aft of said bag.

6. A life preserver including a flexible 70 bag having a rectangular frame, a pocket-book closure therefor, and buoyant means flexibly connected to said frame on opposite sides to support said bag.

7. A life preserver including a flexible 75 bag having a rectangular frame, a pocket-book closure therefor extending upwardly and hinged to said frame, and buoyant means flexibly connected to said frame on opposite sides to support said bag. 80

8. A life preserver including a flexible bag having a rectangular frame, a pocket-book closure therefor including two members hinged to said frame and extending upwardly therefrom, flexible air conduits attached to said hinged members and communicating with the interior of said bag, and buoyant means flexibly connected to said frame on opposite sides to support said bag. 85

In testimony whereof I affix my signature 90 in presence of two witnesses.

NICK K. RAMOS.
